UNITED STATES PATENT OFFICE.

ROBERT ANDERSON, OF SCHENECTADY, NEW YORK, ASSIGNOR TO GENERAL ELECTRIC COMPANY, A CORPORATION OF NEW YORK.

MAGNETIC CLUTCH.

No. 882,607.

Specification of Letters Patent.

Patented March 24, 1908

Application filed September 18, 1906. Serial No. 335,079.

To all whom it may concern:

Be it known that I, ROBERT ANDERSON, a subject of the King of Sweden, residing at Schenectady, county of Schenectady, State of New York, have invented certain new and useful Improvements in Magnetic Clutches, of which the following is a specification.

My invention relates to magnetic friction clutches, and its object is to provide a novel clutch construction of high efficiency, in which the clutch parts are wholly inclosed.

One feature of my invention consists in providing a clutch-magnet with two armatures arranged on opposite sides of the magnet movable towards each other into engagement therewith. This construction gives a large frictional drag with a small magnetizing current as compared with structures employed heretofore.

My invention further consists in providing a casing carried by either the driving or driven shaft completely inclosing the magnet and armatures, so as to protect them from injury, and still further consists in arranging this casing so that it forms a suitable drum for a band brake, thereby particularly adapting the clutch for use in hoists and similar work.

My invention will best be understood by reference to the accompanying drawings, in which

Figure 1 shows a cross-sectional view of a clutch constructed in accordance with my invention; Fig. 2 shows an end view with a portion of the casing and one of the armatures removed; and Figs. 3 and 4 show similar views of a modified construction.

Referring first to Figs. 1 and 2, A and B represent two axially-alined shafts, of which A may be the driving shaft, and B the driven. C represents the clutch-magnet which is carried by and surrounds the shaft A. D represents the magnetizing winding, which extends circumferentially around the shaft, and is connected to collector-rings d. The magnet C is formed with radially projecting poles, all of which lie in the same plane, but which extend outward alternately from opposite sides of the winding D. Alternate poles are, consequently, of the same polarity. E represents an inclosing casing, which is fast to the shaft B, and which completely incloses the magnet C. This casing may be sleeved on the shaft A, as shown, so as to

make an air-tight inclosure for the magnet. 55 Two armatures F are keyed on the inner periphery of the casing E on opposite sides of the poles of the magnet C. Compression springs G are placed between the armatures, so as to hold them away from the magnet C, as 60 shown in Fig. 1, when the winding D is not energized. When the winding is supplied with current, both armatures F are simultaneously drawn axially into frictional engagement with the poles of the magnet C, so 65 as to transmit power from one shaft to the other. The periphery of the casing E forms a suitable drum for a band brake H, which may be controlled in any well known manner, either mechanically or electrically, 70 through the pivoted lever I. The clutch is consequently well adapted for use in hoists and other apparatus requiring a brake.

In the construction shown in Figs. 3 and 4, the magnet C is arranged without poles and 75 consists of a disk-shaped member formed of two parts in the shape of concentric rings, between which is mounted the magnetizing coil D. This coil is held in place between two rings d', which may be of brass or other 80 non-magnetic material, which serve to unite the two rings which form the magnet C. In the construction shown in these figures the flux produced by the coil D passes through the two armatures in series. The arrangement of the compression springs G is slightly 85 different from that shown in Fig. 1, but otherwise, the construction is similar. The band brake is not shown in these figures.

Many other modifications in the construction and arrangement of parts may be made without departing from the spirit of my invention.

What I claim as new and desire to secure by Letters Patent of the United States, is,— 95

1. A magnetic clutch comprising a magnet, an energizing winding therefor, and two mechanically connected armatures on opposite sides of said magnet movable towards each other into engagement with said magnet, the magnet being arranged to attract both armatures simultaneously. 100

2. In a magnetic clutch, in combination with a shaft, a magnet carried by and surrounding the shaft, an energizing winding therefor, and two mechanically-connected ring-shaped armatures on opposite sides of said magnet axially movable into engage- 105

ment with said magnet, the magnet being arranged to attract both armatures simultaneously.

3. A magnetic clutch comprising a magnet, an energizing winding therefor, two mechanically-connected armatures on opposite sides of said magnet movable towards each other into engagement with said magnet, the magnet being arranged to attract both armatures simultaneously, and compression springs between said armatures adapted to move them apart when said engaging winding is deenergized.

4. In a magnetic clutch, in combination with a shaft, a magnet carried by and surrounding the shaft, an energizing winding therefor, two mechanically-connected ring-shaped armatures on opposite sides of said magnet axially movable into engagement with said magnet, the magnet being arranged to attract both armatures simultaneously, and compression springs between said armatures adapted to move them apart when said energizing winding is deenergized.

5. In a magnetic clutch, in combination with axially-alined driving and driven shafts, a magnet carried by and surrounding one of said shafts, an energizing winding therefor, and two ring-shaped armatures carried by the other shaft on opposite sides of said magnet and axially movable into engagement therewith, the magnet being arranged to attract both armatures simultaneously.

6. In a magnetic clutch, in combination with axially-alined driving and driven shafts, a magnet carried by and surrounding one of said shafts, an energizing winding therefor, two ring-shaped armatures carried by the other shaft on opposite sides of said magnet and axially movable into engagement therewith, the magnet being arranged to attract both armatures, and a casing carried by one of said shafts inclosing the magnet and the armatures.

7. In a magnetic clutch, in combination with axially-alined driving and driven shafts, a magnet carried by and surrounding one shaft, an energizing winding therefor, a casing carried by the other shaft inclosing said

magnet, and two armatures carried within 50 said casing on opposite sides of said magnet and axially movable into engagement therewith, the magnet being arranged to attract both armatures simultaneously.

8. In a magnetic clutch, in combination 55 with axially-alined driving and driven shafts, a magnet carried by and surrounding one shaft, an energizing winding therefor, a casing carried by the other shaft inclosing said magnet, two armatures carried within said 60 casing on opposite sides of said magnet and axially movable into engagement therewith, the magnet being arranged to attract both armatures simultaneously, and compression 65 springs between said armatures adapted to move them apart when said energizing winding is deenergized.

9. In a magnetic clutch, in combination with axially-alined driving and driven shafts, 70 a magnet carried by and surrounding one shaft, an energizing winding therefor, a casing carried by the other shaft inclosing said magnet, two ring-shaped armatures keyed on the inner periphery of said casing on opposite sides of said armature and axially 75 movable into engagement therewith, and compression springs between said armatures adapted to force them apart when said energizing winding is deenergized.

10. In a magnetic clutch, in combination 80 with axially-alined driving and driven shafts, a magnet carried by and surrounding one of said shafts, an energizing winding therefor, two ring-shaped armatures carried by the other shaft on opposite sides of said magnet 85 and axially movable into engagement therewith, the magnet being arranged to attract both armatures, a casing carried by one of said shafts, inclosing the magnet and armatures, and a brake-band engaging the periphery of said casing. 90

In witness whereof, I have hereunto set my hand, this 17th day of September, 1906.

ROBERT ANDERSON.
